UNITED STATES PATENT OFFICE.

HERBERT M. FRIENDLY, OF PORTLAND, OREGON.

TELEPHONE SYSTEM.

Application filed March 3, 1922. Serial No. 540,779.

The present invention relates to automatic telephone systems in which selector switches are employed. More specifically, the invention relates to an improved method and apparatus whereby certain mechanism of selectors is dispensed with, and apparatus units involving essentially the displaced mechanism provided. The apparatus units are arranged so that they will automatically associate themselves with a seized selector. Thus, when a selector becomes seized, by an antecedent line switch, for example, if it is not at the time associated with an apparatus unit cooperative therewith, it will be come forthwith so associated by reason of the cooperative apparatus unit hunting for and seizing the said seized selector. When a selector has an apparatus unit in seized relation with it, as referred to, the selector becomes directly controllable as if it involved only permanently related component elements.

In incorporating the present invention, I provide apparatus units in smaller number, one-twentieth as many, for example, as there are selector units, and provide each apparatus unit with a driving mechanism which will automatically initiate its functioning upon a cooperative selector being seized by a line switch, and cause it to hunt over bank contact sets until the said seized selector is found. It will not again hunt until a selector cooperative to the apparatus unit is thereafter seized. However, when the selector with which the apparatus unit becomes associated in seized relation is caused to operate and select and seize a trunk of a called group, the embracing apparatus unit will become operatively disassociated from the last said selector, so far as being effective to its linking conductors, or the operative functions thereof is concerned. The apparatus unit thus contains control elements (relays, for example), which are adapted to be automatically temporarily associated with selector elements to form a complete selector unit.

It will appear that because of eliminating certain elements of the selector units, the latter said units will involve less cost and carrying charges, and require less containing space. Also, due to the simplified arrangement, they will involve less maintenance, and, moreover, will admit of incorporating desirable operative functions (not incorporated in the exemplified system), which due to

cost of additional elements, would not be admissible were it required to individually equip each selector unit of an exchange to itself incorporate the said referred-to desirable functions. The employed method of "lapping" the connections between the groups conduces toward a uniform distribution of the traffic, since there is a like relation between each line switch group and all selector groups. 60

In order to make the disclosure as simple and brief as possible, I have chosen a selector circuit, well known in the art, and have introduced such changes therein as are 70 needed, in order for it to operate in accordance with the present invention.

It will appear that the selectors involved in the present invention, wherein they are controlled by a temporarily associated apparatus unit, may be cooperated in seized relation with selectors of well known types, that is, may seize or be seized by selectors of well known type. However, the descriptions in the exemplified system show the selector of the present invention seized by the line switch. In view of the fact that selectors of well known types seize under conditions similar to those of line switches of the illustrated type, and introduce generally like conditions into the linked circuits, the adaptation wherein a selector is substituted for the line switch will be manifest. The selectors of the present invention may manifestly be employed to terminate trunks of any numerical 80 order, and are therefore not restricted to use to the first numerical order, as shown, by way of example. 85

Reference is made to my Patent No. 1-, 565,269, granted December 15, 1925, on an 95 application filed March 30, 1922, Ser. No. 548,165. Also, my pending application filed December 16, 1921, Ser. No. 522,842, and my pending application filed October 24, 1921, Ser. No. 510,016. 100

Referring to the drawings:—

Fig. 1 is an apparatus unit A, and four of the cooperating bank contact sets of the present invention.

Fig. 2 is a selector B² of the present invention, cooperative with A. 105

Fig. 3 is a selector C³ of the present invention, similar to selector B², cooperative with A.

Fig. 4 indicates a second selector S⁴ of well known type, cooperative with the first 110 selectors B² and C³. It also indicates a con-

connector C^4 of well known type, reached through the selector S^4 . The connector C^4 has access to the line leading to telephone T^4 , and other lines not shown.

5 Fig. 5 shows a substation telephone T^5 leading to a line switch D^5 . The line switch D^5 has access to selector B^2 and other selectors of its group.

10 Fig. 6 shows a substation telephone T^6 leading to a line switch E^6 . The line switch E^6 has access to selector C^3 and other selectors of its group.

15 Fig. 7 shows a diagrammatic layout of a portion of the exemplified system, but showing an arrangement which may be alternatively employed with relation to the apparatus units and respectively embraced selectors.

20 Fig. 8 shows a diagrammatic layout of a portion of the exemplified system with relation to apparatus units and respectively embraced selectors.

25 Fig. 9 shows the assembly of the various figures to display the exemplified system. Lines extending toward adjacent margins which register are to be understood as extensions of the same line joining terminals. Lines extending toward margins which do not register with lines extending toward 30 adjacent margins indicate multiplied elements of those shown may be attached.

35 The telephones T^4 , T^5 and T^6 are of the general class, and in fact may be assumed as of the generally similar type as the telephone designated A in U. S. Patent No. 13,901, reissued to Frank Newforth, April 13th, 1915.

40 Line switches D^5 and E^6 are of the general class as shown in U. S. Patent No. 1,193,160, granted to Lamb, August 1st, 1916. They are of the exact type shown in my pending application, Serial No. 510,016, filed October 24th, 1921.

45 The first selectors B^2 and C^3 , when cooperated in seized relation with the apparatus unit A, respectively, comprise a complete selector of the general class shown in U. S. patent to Keith, Erickson & Erickson, No. 815,321, granted March 13th, 1906, 50 of course, modified in mechanical and circuit details to operate on the well known so-called two-wire principle, and in accordance with the present invention.

55 The second selector S^4 may be assumed to be of the exact type as selector E of the said cited patent to Newforth.

60 The connector C^4 may be assumed to be of the exact type as connector H of the said cited patent to Newforth.

65 Referring further to Fig. 1, the apparatus unit A has access through its wipers and cooperating circumferentially spaced bank contact sets with a plurality of first 125 selectors of which selectors B^2 and C^3 are two, the wipers of the said apparatus unit

being shown resting upon the bank contact set corresponding to selector B^2 . That is to say, the selector B^2 , together with apparatus unit A can form a complete selector unit. In this connection it will be understood that while one only apparatus unit is

70 shown cooperative with selectors B^2 and C^3 , a plurality of such apparatus units may so cooperate through sets of corresponding bank contacts in multiple relation. Under

75 the latter method of operation all apparatus units would have common relation with all the embraced selectors and common conductors, the first apparatus unit to gain the seizure of a selector which has become seized by a line switch serving to set up a condition whereby the remaining apparatus unit or units will stop hunting. Under this lat-

80 ter method of relating a small plurality of apparatus units with a larger plurality of 85 selectors the hunting time will be generally reduced, since the apparatus unit having its wipers nearest to the selector requiring an apparatus unit will be the one to seize.

85 It will be noted that in introducing a second or plurality of apparatus units; each embracing the same group of selectors commonly, the resting contacts of armatures corresponding to 112 will be multiply attached to conductor 215 in order that the motor

90 magnet as M of all idle apparatus units will be energized responsive to a selector being seized by a line switch. Also, the grounded make contact cooperative with armature 176 of apparatus unit A will be extended to armature corresponding to 176

95 of the next apparatus unit of the group; being continued in this manner to the armature corresponding to 176 of the last apparatus unit, which latter armature cooperates with a grounded working contact as shown in apparatus unit A. Thus, the conductor 216 will not become grounded to bar

100 the idle selectors of the group embraced by said plurality of apparatus units unless the conductor 216 is chained to ground, as when a single apparatus unit is employed as shown in the drawings illustrative of the simplest embodiment.

105 By referring to Fig. 8, it will be noted that there are three groups of line switches, F, G and H, each group of which contains three line switches. In commercial practice each group would perhaps contain three hundred line switches, terminating an equal number of respectively corresponding substation lines. Also, in commercial practice, in place of there being three groups of line switches, there would perhaps be twenty groups. However, the numbers (3) shown

110 in Fig. 8 will suffice to exemplify the present invention, without unduly involving the drawings and descriptions.

115 With further reference to Fig. 8, it will be noted that substation T^5 leads to line 120 130

switch D⁵ in group F, and that substation T⁶ leads to line switch E⁶ in group H. It will also be noted that the bank positions in the line switches D⁵ and E⁶ numerically 5 correspond, though they are not multiplied. Of course, this numerical relation has no operative significance, beyond having a uniformity in order to facilitate simplicity in the record system, looking towards ready 10 tracing of connections. However, it will be observed that the same apparatus unit A has access to the selectors B² and C³, and also to other selectors belonging to other groups which are connected to corresponding 15 bank positions in the line switches of the other groups. That is to say, numerically corresponding bank contact sets of the various groups of line switches refer to the same group of selectors. For example, 20 should there be twenty groups of line switches each having twenty-five sets of bank contacts there would be twenty-five groups of selectors. The same number of groups of selectors would be employed if 25 there were more or less line switch groups, since the number of groups of selectors depends upon the number of sets of bank contacts of the line switches, each set of bank contacts corresponding to a group of selectors. 30 It will thus appear, that the first set of bank contacts of all the line switch groups correspond to the first group of selectors. Similarly, the third set of bank contacts of all line switch groups correspond to the 35 third group of selectors, etc. Generally, stated, there are a plurality of line switch groups, each said group having access to a group of selectors, wherein the numerically corresponding located selectors of the said 40 selector groups (with respect to the bank contacts of the line switches) taken together, constitute a divisional group accessible to an apparatus unit. By way of still further explanation, each selector group accessible 45 to or embraced, as it were, by an apparatus unit, contains one selector from each selector group accessible to a group of line switches, and therefore, each selector group accessible to a line switch group has in it 50 one selector (or more, as will appear presently) of each group embraced by each apparatus unit. However, attention is called to selector J accessible to the line switches of group H. The selector J is embraced by 55 the apparatus unit A. The apparatus unit A therefore has access to two selectors reached through the line switch group H. It is manifestly possible to have the apparatus unit A embrace additional selectors 60 of the said group H, and in fact, additional selectors located in numerical correspondence with relation to the banks of the line switches in groups G and F, though the numerical correspondence will have no operative 65 significance. Under the method of

having an apparatus unit embrace a plurality of selectors accessible to a line switch group will, in effect, reduce the number of apparatus units and selector groups to be employed, assuming that the same number 70 of selectors would be embraced by the apparatus unit in each case. The latter described alternative arrangement lends itself where a relatively small number of first selectors are required to handle the traffic. 75

It will appear presently, that if a selector of any group is seized by a hunting line switch, all selectors of the group become temporarily barred against seizure, by reason of a false busy condition being thereby set-up with relation to the group containing the seized selector. When the selector has been operated so that it seizes a called trunk, the set-up false busy condition becomes thereby removed, so that an idle 80 selector of the group is thereafter subject to seizure by a line switch of any group. It will be understood, in view of foregoing statements, that corresponding bank contacts of all line switches refer to a numerically corresponding group of selectors, each group of selectors being commonly embraced by an apparatus unit which will be enabled 85 to be in cooperative relation with but one of the selectors thereof at any time, and it 90 will be resting at the bank position corresponding to the last selector of its embraced group employing it, from whence it will automatically function by way of hunting, 95 when its subsequent requirement occurs. 100

When a hunting line switch finds a set of bank contacts thereof busy, by reason of the corresponding selector being busy or due to a false busy condition being found, the corresponding set of bank contacts will be 105 passed over and the successive set tested. It will appear presently how, if any apparatus unit is not free (that is, in a seized relation to a set of bank contacts, or is hunting), its embraced selectors will not be subject to seizure by a line switch, but as soon as the apparatus unit becomes free any idle 110 selectors embraced by it become subject to seizure.

Incidental to a selector becoming seized by a line switch, a ground is placed upon a first common conductor of the group to guard other selectors of the group, as well as the seized selector temporarily, and this ground is maintained until the apparatus 120 unit becomes free. Also, the seized selector, through the actuation of its relay, resultant to the seizure, applies a ground to another common conductor of the group for the purpose of initiating the hunting operation of 125 the embracing apparatus unit. Under the condition of a selector being seized by a line switch, the embracing apparatus unit will be thus caused to hunt for and find it, whereby the latter said selector will be thereafter 130

capacitated to function under directive control, and a tone will be applied audible to the calling party to index the ready condition of the selector, so directive impulses 5 may be forthwith applied. The ground placed upon the said first common conductor which temporarily guards the last seized selector, becomes forthwith disassociated from the last seized selector upon its relay 10 actuating, the latter said selector being thereafter guarded by ground on its private conductor attaching to the private bank contacts of accessible line switches. However, the said first common conductor is maintained 15 grounded from the selector, and also, from the embracing apparatus unit when it seizes the selector, and this ground is maintained until the selector seizes the trunk leading to the second selector, through its relay fully 20 actuating, or until the call is destroyed before such actuation takes place.

In view of the fact that from the time a selector is seized by a line switch until the selector has been directly operated, and it 25 has thereafter seized a trunk, not more than two seconds have elapsed, on the average, and in further view of the fact that the selectors are thereafter held on the average of say, eighty seconds before being released, 30 it will appear that one apparatus unit could possibly serve forty selectors. If enough selectors are provided so there will always be an idle one available, the condition simply resolves itself into that of the line switch 35 of a calling line finding a selector of a group having an idle apparatus unit, bearing in mind that successive sets of bank contacts hunted over by the line switch each refer to a selector of corresponding different selector 40 groups, and that the same selector will not be tested twice, unless all groups are found busy and a re-testing occurs, the line switch continuing to hunt until an idle selector is found. However, the arrangement shown in 45 Fig. 7 (also having in mind the disposition of selector J referred to, and which is different from the one about to be described), contemplates that re-testing in a group shall occur by reason of the fact that selectors 50 of the same group are interspersed. That is to say, if a selector of a group is encountered as busy, the line switch will test another selector of the same group after it has hunted over a number of other selectors belonging 55 to other groups. For example, the first, third and fifth set of bank contacts of the line switches refer to the same group of selectors, though not to the identical selectors of the said groups. Of course, if a false 60 busy is applied to all the selectors of a group by reason of the apparatus unit embracing them being busy, all selectors of the group will test busy to a hunting line switch, as shown in the arrangement set forth in Fig. 8. 65 In comprehending the arrangement shown

in Fig. 7, it will be remembered that the line switches have no normal resting position, and will therefore rest where last employed, so that the wipers of the various line switches will be deployed over the entire 70 group of accessible bank contact sets, and thus the same selectors will not be tested for in a predetermined order, upon calls being initiated.

Referring to selector B², it will be understood that the general mechanical arrangement is the same as that of selector E of the said cited patent to Newforth. However, a set of off-normal springs RO² are provided, which only operate when the shaft 75 carrying the wipers rotate off-normal. The set of off-normal springs VO² operate when the wipers step off-normal (vertically) primarily. The relay S², which functions as a switching and a release relay, has two 80 windings. The upper winding, when energized causes the relay to fully operate. The lower winding (due to its high resistance and disposition), when alone energized 85 serves to operate only the four armatures (209, 212, 211 and 213), shown in solid black. Due to a restraining spring, the lower-most armature will not engage its make contact, though it will disengage its resting contact. The off-normal spring sets RO³ and VO³ in 90 selector C³ correspond as to function with sets RO² and VO² in selector B², respectively. Similarly, relay S² and S³ have the same 95 characteristics.

Having in mind the location of the equipment elements T⁵, T⁶, D⁵, E⁶, B², C³ and A, in Fig. 8, it will be assumed that a call is initiated at substation T⁵. A circuit path can be traced from the winding of slow-releasing line relay 501, armature 502, line 100 conductor 503, receiver of substation T⁵ conductor 504, armature 505 to group relay 501 actuating. If it is now assumed that the set of bank contacts 506 to 509 (inclusive) upon which the wipers 512 to 515 of line switch D⁵ are shown resting (respectively) is busy, because of the corresponding selector B² being busy by reason of it having been seized and held due to a previously 110 initiated call, private bank contact 509, and its multiples appearing correspondingly in other line switches of its group, will constitute ground, as will appear presently. Under the latter condition a circuit path will exist from the said grounded bank contact 509, wiper 515, armatures 517, 518 and 519 to the winding of the motor magnet M⁵, the said motor magnet operating to interrupt the latter traced path in the well known manner to cause the wipers 512 to 515 to be advanced into engagement with bank contacts 521 to 524, the latter corresponding to a selector similar to B², not shown. If bank contact 524 also constitutes ground the motor magnet M⁵ will be caused to further 120 ad- 125 130

vance the wipers as before, the cycle of advancing operations continuing until wiper 515 fails to receive ground from an engaged bank contact, it being remembered that the 5 line switch D^5 has its bank contact sets spaced radially and that it will successively test in a hunting operation consequent to a call being initiated on its leading-in line. As has been referred to, and as will further 10 appear presently, the line switch D^5 will hunt and successively test wherein hunted-over selectors may be idle, but falsely guarded against seizure.

It will be assumed that bank contacts 509 15 and 524 do not primarily constitute ground, but that bank contact 506 (and 509) does constitute ground, due to a falsely set-up condition effectuated from the apparatus unit A or an embraced selector thereof. In 20 view of armature 525 being retracted, wipers 512 and 515 are electrically tied, so the functioning of the line switch will be the same, regardless of which wiper 512 or 515 primarily receives ground.

25 It will be assumed that the bank contacts 506 and 509 do not constitute ground at the time the call is initiated, and therefore, ground will not be applied to the winding of the motor magnet M^5 , which latter condition not only served to operatively energize the motor magnet, but applied a ground short-circuit to the lower winding terminal of the switching relay 527, so that in view of the upper winding terminal thereof being grounded on armature 528, it is disabled 30 from becoming energized. A circuit path can now be traced from the winding of motor magnet M^5 , armature 519, winding of relay 527, to grounded armature 528, the 35 relay 527 actuating, the motor magnet M^5 , due to its marginal adjustment, not operating. The conductors 503 and 504 are thus continued through armatures 502 and 505, wipers 513 and 514, bank contacts 507 and 40 508, conductors 531 and 532, respectively. At the time armature 517 attracts, ground is applied from armature 528, armature 517, wiper 515, bank contact 509, conductor 533 45 (and multiples), off-normal springs, upper winding of relay S^2 , resistance r^2 to grounded battery, the relay S^2 actuating by way of operatively attracting all its armatures. Since the wipers 203 to 205 are free, the attracting of the armatures 206 to 208 50 will have no operative effect at this juncture. Also, since the off-normal spring set RO^2 is normal, the full attracting of the lower-most armature 209 will have no operative effect at this juncture. However, a momentary locking circuit path will be completed 55 from the armature 210, off-normal springs to the upper winding of relay S^2 , and also to conductor 533. This momentarily locked condition of relay S^2 will be forthwith 60 destroyed, causing all armatures, excepting 65

those shown in solid black to retract, as will appear presently. The said ground is applied to conductor 533 before the relay 501 has had time to deactivate, so that no lapse of ground occurs to conductor 533. The 70 uppermost armature 211 being attracted, disconnects the conductor leading to bank contact 506 and its multiples from common conductor 212. Ground from armature 212 is applied through off-normal contacts to 75 common conductor 215, armatures 112, 113 and 114 to the winding of motor magnet M. Ground from armature 212 is also applied through off-normal contacts to common conductor 216 to falsely guard the accessible 80 line switches against seizing an idle selector of the group embraced by the apparatus unit A, as will appear presently. However, a circuit path is coincidentally completed with the latter said paths from grounded off-normal 85 spring, armature 213, conductor 214, bank contact 126, wiper 146 to the winding of slightly slow-releasing relay 148, the latter said relay actuating to open the former traced path to the winding of the motor 90 magnet M. Armatures 149, 150 and 181 on relay 148 are provided for an object which will appear presently.

In the last foregoing descriptions the apparatus unit A is in associated relation with 95 the bank contact set thereof corresponding to the selector B^2 , when the latter said selector is seized. This condition will not usually occur, since if the apparatus unit embraces twenty selectors, for example, there 100 will be a possibility of one to twenty that the seized selector will not have the embracing apparatus unit associated with it when seized, as is shown in the drawing with reference to selector B^2 . The operative functioning under the condition wherein the apparatus unit is not in associated relation 105 with the seized selector will be discussed presently.

Going back to the condition ensuing incidental to the actuation of relay 527, it will appear that a circuit path will be closed from the upper winding of relay 151, armature 152, wiper 135, bank contact 115, conductors 153, 531, and over the path traced 110 including the receiver at substation T^5 , conductors 532, 217, bank contact 125, wiper 145, armature 154, to the lower winding of relay 151, the latter said relay actuating, followed by slow-releasing dependent relay 115. A circuit path can now be traced from ground, armature 156, wiper 136, bank contact 116, conductor 157 to the upper winding terminal of relay S^2 . The latter ground 120 is thus applied in multiple with the locking ground from armature 210. Ground is applied from armature 158, wiper 137, bank contact 117, conductor 159 to conductor 533, the latter applied ground being in multiple 125 with ground from armature 210. If the ar- 130

mature 210 retracts, there will be no lapse of ground to conductor 533, so relay 527 will remain actuated and the selector B² guarded against seizure. A circuit path can 5 be traced from grounded armature 160, wiper 143, bank contact 123, conductor 161 to the lower winding of relay S², the latter said relay being now energized by both its windings cumulatively. Armature 181 on 10 relay 148 being attracted, ground will be applied therethrough, wiper 138, bank contact 118, conductor 172 to the live terminal of the upper winding of relay S², thus short-circuiting the said upper winding. In view 15 of the short-circuited winding, and characteristics, the relay S² is slow-releasing under the condition, thus allowing armature 160 to apply its ground to the lower winding of said relay S² before the energizing 20 path of relay 148 is opened by the retraction of armature 213, which latter does not occur at this juncture. However, all armatures, excepting those shown in solid black do retract, and the lowermost (solid black) 25 armature 209 does retract from its make contact. The armature 158 attracts to apply ground to conductor 533 before armature 210 retracts, so no lapse of ground occurs to conductor 533, by reason of the upper winding of relay S² being deenergized as set forth. The object of deenergizing the latter said winding of relay S² will appear presently.

It will be assumed that the first digit "1" 30 is sent from the calling device at substation T⁵, causing relay 151 to deactuate and re-actuate one time responsive thereto. Armature 163 will apply its ground to wiper 144, bank contact 124, conductor 164, rotary off-normal springs, conductor 218, bank contact 120, wiper 140, armature 165 (relay 155 sustaining over the current lapse), winding of slow-releasing series relay 167, wiper 142, bank contact 122, conductor 168 to the vertical magnet VM², the latter said magnet operating by way of raising the shaft carrying wipers 203 to 205 into alignment with the first level of bank contacts, the relay 45 167 actuating coincident with the magnet VM². Armature 169 will apply ground received from armature 158 to the winding of the shunted interrupter relay 170, causing it to actuate. At the time relay 170 actuates 50 resultant to the relay 167 energizing, the vertical off-normal springs VO² operate, opening the energizing path of relay 148, so that armature 181 retracts. However, armature 171 applies its ground before armature 181 retracts, insuring the maintenance of 55 ground on conductor 172. The latter said grounded condition of conductor 172 is now dependent upon relay 170 remaining locked (as will appear presently) to said conductor 172, which latter conductor is now grounded 60 at armature 171 of relay 170 in lieu of 65

at armature 181 where it was initially applied.

Under the last foregoing condition, that of conductor 172 being grounded, the upper winding of relay S² is unenergized, but the 70 lower winding of relay S² is energized, since armature 160 is attracted. The armatures of relay S², excepting those shown in solid black are now retracted, the lowermost armature 209 being retracted from its make 75 contact, but attracted from its resting contact.

The relay 170 is locked by way of armature 173, wiper 141, bank contact 121, conductor 221, upper set of off-normal springs, 80 armature 220 to grounded conductor 172. If the path is opened, as at armature 220, incidental to the actuation of the rotary magnet RM², the relay 170 will deactuate, armature 171 removing the ground from 85 the conductor 172. However, ground applied through wiper 203 and retracted armature 206 would serve to reground it upon the retraction of the said armature 220, whereupon the relay 170 will reactuate and 90 lock through its armature 171.

Upon armature 169 retracting, following the impulse to the vertical magnet VM², a circuit path can be traced from ground on armature 158, armatures 169, 174, wiper 139, 95 bank contact 119, conductor 175 to the rotary magnet RM², the latter said magnet operating by way of advancing wipers 203 to 205 one rotary step into engagement with bank contacts 223 to 225. Incidental to the rotary 100 magnet operating, its armature 220 will open the described locking path for the relay 170, as referred to, so the latter said relay will deactuate. Armature 209 being attracted from its resting contact, though the vertical 105 off-normal set VO² is operated, prevents the release magnet Re² from being energized. The armature 211 being attracted prevents the conductor leading to bank contact 506 (and multiples) of the line switch D⁵ becoming 110 grounded on conductor 216, the latter conductor now receiving ground through armature 176 of the apparatus unit A.

It will be assumed for the present that the second selector S⁴, corresponding to the 115 set of bank contacts 223 to 225, is busy, and therefore the bank contact 223 constitutes ground when engaged by wiper 203. Under such condition, when the wiper 203 receives ground from bank contact 223 and 120 armature 206 is then in a retracted condition, the said ground serves to ground the live terminal of the upper winding of relay S² at the right-hand terminal of resistance r², and to also apply this ground through 125 armature 220 on the rotary magnet, vertical off-normal springs, conductor 221, bank contact 121, wiper 141, armature 173 to the winding of relay 170, the latter said relay actuating, whereupon a locking circuit for it 130

becomes established over the before traced path, and in view of armature 169 being retracted, the rotary magnet RM² will energize over the before traced path, by way of advancing the wipers a further rotary step. The cycles of functioning by way of automatically advancing the wipers to successive sets of bank contacts re-occur until the wiper 203 fails to receive ground to maintain the ground on the right-hand terminal of resistance r² and to reenergize the relay 170. When the wiper 203 fails to receive ground, the relay 170 will not be caused to re-actuate and cause the rotary magnet RM² to operate, and moreover, the upper winding of relay S² will energize over the before traced path to armature 156 and thereby effect the seizure of the selector B².

Going back to the condition wherein the wipers 203 to 205 engaged bank contacts 223 to 225, and assume that the bank contact 223 does not constitute ground. When the relay 170 unlocks consequent to the attraction of the armature 220 on the rotary magnet RM² incidental to the first rotary movement of the wipers 203 to 205, the ground is thereby removed from the right-hand terminal of resistance r², so that the upper winding of relay S² will become energized over the before traced path by way of armature 156, the selector B² thus seizing. A circuit can now be traced from bank contact 224, conductor 230 to the upper (battery) winding of the line relay in second selector S⁴, and from the lower (ground) winding of the said line relay, conductor 401 to bank contact 225, so that due to armatures 207 and 208 being attracted, the receiver at substation T⁵ is now energized in series with the battery and ground windings of the line relay of the selector S⁴. The release relay in the selector S⁴ will cause conductor 402 to project ground back to bank contact 223, wiper 203, armature 206, conductor 157, free winding terminal of the upper winding of relay S², maintaining the selector B² seized. The latter ground is applied before the armature 156 retracts, so no lapse of ground occurs to conductor 157. The armature 156 will retract, due to the fact that when armature 209 becomes fully attracted, its ground is applied through rotary off-normal springs, conductor 222, bank contact 127, wiper 147 to the winding of slow-releasing relay 179, causing the latter said relay to actuate to disassociate the windings of relay 151 from talking conductors 531 and 532, whereupon the latter said relay will de-actuate, followed by relay 155. It will be noted in this connection, that when armature 206 attracts, and while it is receiving ground over conductor 402, a low battery potential will exist on conductor 172, which will be applied through armature 220, upper set of vertical off-normal springs, con-

ductor 221, bank contact 121, wiper 141, armature 173 to the winding of relay 170, but the current thus derived through the winding of relay 170 is not sufficient to operatively affect it. Armature 112 being now retracted, the motor magnet M will become operatively energized consequent to any selector of the group embraced by the apparatus unit A becoming seized, whereby the common conductor 215 will become grounded in the manner before described.

In this connection, attention is directed to the fact that when a line switch as D⁵ is hunting over busy bank contact sets, wherein the wiper 515 receives ground, the wiper 512 will also receive ground, since the two latter said wipers are tied through armature 525. This will mean that bank contacts engaged by wiper 512 will be grounded while the line switch is hunting. However, the latter grounding of bank contacts will have no operative effect through the common conductor 216, from the fact that when the selector B², corresponding to bank contact 506, for example, seized or remains seized, whereby the armature 211 of relay S² is attracted, the conductor leading from bank contact 506 (and multiples), is opened. Under the condition of relay S² being actuated, or the selector B² is in a seized condition from a line switch, said selector B² will be guarded against seizure, by reason of the ground applied to conductor 533 from armature 210, or from armature 158 of the apparatus unit A. Were it not for the provision of armature 211, hunting line switches of the group would apply ground received through the wiper thereof corresponding to 512, and the engaged bank contact to common conductor 216, and from the latter conductor to all contacts engageable to wipers corresponding to 512. So that under the condition of a line switch hunting over busy bank contacts, it would incidentally place a false busy guard, preventing the seizure of any of the selectors of the group to other simultaneously hunting line switches, otherwise adapted to be seized. On the other hand, when the common conductor 216 becomes grounded while the apparatus unit A is busy, as set forth, all idle selectors of the group embraced by the said apparatus unit will become falsely guarded against seizure thereby, bearing in mind that selectors of the latter said group which are actually busy, will be guarded against seizure by reason of the private conductor thereof corresponding to 553 constituting ground. Manifestly, a selector embraced by the apparatus unit A, for example, must not be seizable unless the said apparatus unit is free, as otherwise there would be no means to adapt the seized selector to make it responsive to directive control.

In view of the tone source DT being in the traced path including the lower winding of relay 151 and the receiver of the calling substation T⁵, the calling party will 6 know that an idle selector has been seized, and that the embracing apparatus unit has operatively associated itself, so that directive calling may be forthwith proceeded with.

Returning to the condition wherein the 10 call was completed to the selector S⁴, where-in the relay S² in selector B² is held actuated from ground received from the selector S⁴. There are no operative attachments to the talking conductors in selector B², the 15 said talking conductors terminating in the two windings of the line relay of the selector S⁴. Upon sending the second digit "1", the selector S⁴ will be caused to function in the well known manner to extend the conductors 20 402, 230 and 401 to conductors 403, 404 and 405, respectively, and to the connector C⁴, ground being maintained on conductor 402 from the said connector in the well known manner. Then, upon the last two digits 25 "1—1" being sent, the connector C⁴ will function in the well known manner to extend the connection to the substation T⁴, the line cut-off relay LCO operating in the well known manner. Armature 176 in apparatus 30 unit A, and armature 525 in line switch D⁵ being attracted, and the vertical off-normal springs VO² being operated, no ground exists on the common conductor 216, nor on common conductor 215, due to the latter 35 stated condition with reference to the vertical off-normal springs.

Should the calling party replace the receiver, thereby deenergizing the line relay in the connector C⁴, whereupon the conductor 402 will become ungrounded, the latter said connector will restore in the well known manner, as well as selector S⁴. Due to relay 40 155 in the apparatus unit having deactuated consequent to relay S² actuating to effect the seizure of selector B², the lower winding of relay S² is unenergized, so the latter said relay will now deactivate because the removal of ground from conductor 402 unenergizes the upper winding of said relay S². The 45 latter function opens the sustaining ground to relay 527 in the line switch D⁵ received from armature 220. It also closes a circuit from the release magnet Re², off-normal springs to grounded, retracted armature 209, the latter said magnet operating to restore 50 the shaft of the selector B² to normal.

Bearing in mind that while the established connection to substation T⁴ existed and the 60 apparatus unit remained with its wipers resting on the bank contacts corresponding to selector B², wherein the relay 179 is held actuated to keep the windings of the line relay 151 disassociated from the said established connection, it will be assumed that a 65 call is initiated from substation T⁶ and that

selector C³ is seized as the first available idle selector. In view of the fact the line switches D⁵ and D⁶ are similar, and that selectors B² and C³ are similar and correspondingly drawn, it is thought unnecessary to a clear understanding to describe in detail the operations with respect to the functioning consequent to the call being initiated and the selector C³ being seized by the line switch of the calling substation. Suffice 70 it to state that common conductors 215 and 216 become grounded, the former said conductor to initiate the operation of the motor magnet M, and the latter said conductor to falsely guard all selectors (except the latter 75 said seized collector C³, which is now guarded through its private conductor) embraced by the apparatus unit A against seizure, if not busy.

The relay S³ in selector C³ will actuate 80 as in the manner of relay S² described, consequent to the line switch E⁶ seizing the selector C³, the relays S² and S³ being alike. This will apply ground from the vertical off-normal springs of set VO³, armature 313, 85 conductor 314 to bank contact 126', accessible to wiper 146 of the apparatus unit A, being the set first successively engaged by wiper 146 upon it rotating from bank contact 126, due to conductor 215 becoming 90 grounded by reason of the attraction of armature 312 of relay S³. Conductor 216 will also be grounded from armature 312. The ground from conductor 215 will energize 95 the motor magnet M over the path before traced, so that the wiper set 135 to 147 will be advanced from the bank contact set 115 to 127 to the next successive bank contact set 115' to 127'. The latter said set of bank contacts have the same relation to selector C³ that the preceding said set has to selector B².

Upon the wiper 146 engaging the bank contact 126', the ground on the latter will 100 be communicated to the winding of relay 148, causing the latter said relay to actuate. The armature 113 attracting, opens the energizing path described to the winding of the motor magnet M, thus disabling the latter said magnet from further automatically advancing the set of wipers 135 to 147 from the set of bank contacts 115' to 127'.

When the motor magnet M operates, its armature 180 applies its ground to the winding of relay 179 for the purpose of maintaining the windings of relay 151 disassociated from the wipers 135 and 145, as otherwise the said windings would become associated with passed-over talking conductors of busy connections, causing disturbance. The relay 179 is made slow-releasing so that 120 it will sustain over current lapses while the armature 180 is in a retracted state for the brief periods in the hunting operation. In view of the delay of establishing the wind- 125 130

ings of relay 151 to wipers 135 and 145 after the set of wipers have stopped upon the set of bank contacts corresponding to the selector embraced by apparatus unit A last seized, a set of supplemental contacts is provided on relay 148 which will forthwith apply the windings of relay 151 to wipers 135 and 145 upon the set of wipers being stopped due to wiper 146 encountering ground, as set forth. The relay 179 will deactivate before the relay 148 will, preventing the windings of relay 151 being falsely disconnected when the seized selector has once become in readiness to receive directive control. It will appear, that while the apparatus unit A has its wipers resting upon a bank contact set corresponding to a selector which has seized the second selector, as for example, when the selector B² seized selector S⁴, the attracted condition of armature 209 causes ground to be applied through rotary off-normal springs, conductor 222, bank contact 127, wiper 147 to the winding of relay 179, before referred to. This will insure that the windings of relay 151 will be disassociated from the talking conductors leading through the selector B². Of course, if the selector B² becomes idle, and the ground is removed from the bank contact 127, the relay 179 will deactivate to re-associate the windings of relay 151.

In relation to the call initiated from substation T⁶, forthwith upon the relay 148 actuating upon the wipers 135 to 147 engaging bank contacts 115' to 127', the tone from source DT will be perceived, indexing that the directive operation of the selector C³ can be proceeded with, wherein the functioning will be as has been fully described with relation to substation T⁶, line switch D⁵, and selector B², the now concerned circuits and equipments being duplicates thereof, having due regard to the fact that the trunk to selector S⁴ is busy, so that an alternative trunk, (not shown) will be seized. Assuming that the last three digits will be "1-1-1", as before, the alternative selector terminating the said alternatively seized trunk will seize an alternative connector of the group containing connector C⁴ (but not shown), and the latter will encounter the called line leading to substation T⁶ as busy, applying the busy tone over the talking conductors in the well known manner. The established connection will be destroyed by replacing the receiver at substation T⁶, as if the call had been completed to the called line, by reason of the fact that ground received from connector C⁴ will be thereby removed from wiper 303. The detailed operation of the selector C³ in this connection, and under its various operative conditions, will be fully comprehended in view of the fact that corresponding elements in Fig. 3 are designated with the index digit "3" to

correspond to the designations in Fig. 2, wherein the index digit "2" is used, and in view of the fact corresponding elements in Fig. 6 are designated with an index digit "6" to correspond to designations in Fig. 5, 70 wherein the index digit "5" is used. Designations in Fig. 1 which refer to selector C³ have a prime added to distinguish from corresponding designations thereon which refer to selector B². 75

It will be assumed that after the line switch D⁵ seized selector B² and the wipers 135 to 147 have engaged bank contacts 115 to 127, and before any directive impulses were sent, the receiver at substation T⁶ is replaced. Relays 151 and 155 will retract, they having attracted consequent to the wipers 135 to 147 engaging bank contacts 115 to 127. This will remove ground from the lower winding of relay S², so the armature 209 (and armatures 211, 212 and 213) will retract, completing the traced path from ground to the winding of the release magnet Re². When the relay 155 deactuates, causing relay S² to fully retract all its armatures, 80 relay 148 will deactivate. However, if in place of restoring the receiver, as assumed, directive impulses had been sent, as was formerly assumed, the vertical off-normal spring set would be operated, incidentally deenergizing the relay 148. The ground applied to the live terminal of the upper winding of relay S² will be removed before relay 167 has been operated and then caused to retract its armature 169, so the armature 181 will not be attracted under the condition of armature 171 locking under the condition of the selector hunting, as otherwise the rotary magnet RM² would be caused to advance after relay 170 unlocked incidental to the ungrounded bank contact being found by wiper 203. 90

It will be assumed that at the time the call is initiated from substation T⁶, the wipers of the apparatus unit in place of being in engagement with the set of bank contacts corresponding to the selector B², as shown in the drawings, has its wipers resting upon the bank contacts corresponding to the selector C³. Upon the selector B² being seized by the line switch D⁵, the described condition is set-up, which it will be remembered included the grounding of common conductors 215 and 216, and the grounding of individual conductor 214; the latter for the purpose of disabling the motor magnet M upon the wipers of the apparatus unit A engaging the set of bank contacts corresponding to selector B², all other selectors of the group embraced by the apparatus unit A being barred against seizure by a line switch due to the grounded condition of conductor 216, and which condition will endure until relay 155 deactuates after selector B² seizes second selector S⁴, notwithstanding that the 100 105 110 115 120 125 130

ground primarily applied to conductor 216 from armature 212 was disconnected incidental to the first off-normal movement of the shaft.

- 5 In view of the last foregoing paragraph, it will be assumed that while the apparatus unit is hunting the set of bank contacts thereof corresponding to the selector B², the calling party replaces the receiver. Under 10 this condition the upper winding of relay S² is locked through off-normal springs to grounded armature 210, the latter said armature also maintaining the line switch D⁵ seized, notwithstanding the calling party 15 has replaced his receiver. It will appear presently that the relay S² will be unlocked, whereby the line switch D⁵ will be restored, so that the equipments are normal, and idle 20 selectors of the group embraced by the apparatus unit A will be subject to seizure. Upon the wiper 146 engaging bank contact 126 and receiving ground therefrom through armature 213, relay 148 will actuate and apply ground through its armature 181, wiper 25 188, bank contact 118, conductor 172 to the live terminal of the upper winding of relay S², causing the latter said relay to completely retract all of its armatures, since there is no energizing path for the windings 30 of relay 151, so that the relay 155 remains deactuated. Under this condition, the lower winding of relay S² does not become energized upon the wipers of the apparatus unit A engaging the bank contact 35 set corresponding to selector B². The off-normal spring set VO² not having actuated, no circuit path is completed to the release magnet Re², though the relay S² is now unlocked, and the line switch D⁵ is unseized. 40 The idle selectors of the group embraced by apparatus unit A are now subject to seizure by a hunting line switch.

In view of the foregoing, it will appear that the object of armature 181 is to forthwith provide a set-up condition in the selector with which a line switch becomes associated, so that in the event the calling party replaces his receiver before the apparatus unit A has had time to associate itself with 45 the latter said selector, or before the latter said selector seizes a second selector, a means will be provided to restore the latter said selector through causing its relay to fully deactuate.

50 The exemplified application of the present invention is but one of many applications thereof, the invention being subject to wide modifications without departing from the scope of it, defined by the subjoined claims.

60 I claim:—

- 65 1. In a telephone system, a group of selective switches, a driving control relay set for said switches common thereto, and selective means responsive to seizure of any one of said switches for selecting the seized

switch and connecting the relay set thereto, the said relay set remaining connected with the said seized switch until a seizure of another one of said selective switches occurs.

2. In a telephone system, a group of selective switches, a driving control relay set for said switches common thereto, selective means responsive to seizure of any one of said switches for selecting the seized switch and connecting the relay set thereto, and means automatically operative following the operation of the said selective switch to operatively disconnect the relay set therefrom and render it available for connection with another one of the switches of the group, the said relay set remaining connected with the said seized switch until a seizure of another one of said selective switches occurs.

3. In a telephone system, a group of selective switches, a driving control relay set for said switches common thereto, selective means responsive to seizing of any one of said switches for selecting the seized switch and connecting the relay set thereto, means automatically operative following the operation of the said selective switch to operatively disconnect the relay set therefrom and render it available for connection with another one of the switches of the group, the said relay set remaining connected with the said seized switch until a seizure of another one of said selective switches occurs, and means responsive to seizure of another one of the selective switches of the group while the first one is still busy to re-operate said selective means to connect the driving control relay set to the last selected switch.

4. In a telephone system, telephone lines, a group of selective switches, means for seizing said switches by said lines for extending calls from said lines, a common driving control relay set for said switches, and selective mechanism for temporarily connecting the relay set to different ones of said switches responsive to seizure of respective said switches in extending successive calls thereafter simultaneously existing, the said connecting being maintained until a successive said seizure.

5. In a telephone system, telephone lines, selective switches for extending calls from said lines, automatic switches for connecting calling lines and the selective switches, a common driving control relay set for said selective switches, selective mechanism responsive to connections of said automatic switches for temporarily connecting the relay set to different ones of said selective switches during the respective driving period, and means for successively operating said selective mechanism responsive to successive calls for successively connecting said relay set to successively selected said auto-

- matic switches whether or not the extended calls are simultaneously existing, the said connecting being maintained until a successive call.
- 5 6. A selective switch having driving apparatus, control relays therefor normally operatively disconnected therefrom and temporarily operatively connected therewith during the driving period, but not individual thereto, means for temporarily operatively connecting the control relays with the said switch, and means for operatively disconnecting the control relays forthwith after each driving period for use in a new call, 10 but leaving the said switch operated, the control relays remaining specifically related to the switch.
7. A selective switch having driving apparatus and control relays therefor temporarily operatively connected therewith during the driving period, but not individual thereto, means for operatively connecting the control relays with the said switch, and means automatically operative for operatively disconnecting the control relays forthwith after each driving period for use in a new call, but leaving the said switch operated, and the control relays inoperatively connected with the selective switch.
- 30 8. A selective switch having driving apparatus and control relays therefor temporarily operatively connected therewith during the driving period, but not individual thereto, cooperating switches, means made operative consequent to the said switch becoming seized by a said cooperating switch for operatively connecting the control relays with the said selective switch, and means automatically operative for disconnecting the control relays forthwith after each driving period for use in a new call, but leaving the said switch operated and the control relays inoperatively connected with the last said switch.
- 45 9. In a group of selectors, each selector having a permanently associated means for operating its wipers responsive to directive control relays applied to its leading-in conductors, a temporarily connected means common to the group for correlating the directive control relays with the permanently associated operating means consequent to a selector of the group becoming seized, and means for releasing the control relays after each operating period for association with another selector for use in a new call, but leaving the operated selector in its actuated position and the control relays inoperatively connected with the said operated selector.
- 60 10. In a telephone system, a plurality of selective switches having individual driving mechanisms, a control relay set, means for temporarily connecting the relay set with one of the selective switches consequent to the last said selective switch becoming seized, and automatic means made operative forthwith upon the termination of the driving period of the said selective switch for disconnecting the said control relay set from a connected said selective switch for use in a new call, leaving the control relay set inoperatively connected with the last said selective switch.
11. In a telephone system, a plurality of selective switches having individual driving mechanisms, a control relay set common to said switches, means for seizing an idle said switch, hunting means made operative consequent to the seizing of the said switch to cause the control relay set to selectively connect itself with the seized said switch and to thereafter operatively disconnect itself upon the seized said switch itself seizing, while retaining its inoperative connection with the last said switch.
12. In a telephone system, calling lines, a plurality of selective switches having individual driving mechanisms, a control relay set common to said switches, selective means for associating the control relay set with any of said selective switches, means for linking a calling line to a said selective switch, means operative consequent to the said linking operation for barring other said selectors against seizure by way of linking a second calling line, means for causing the control relay set to be connected with the said selective switch resultant to it becoming linked, and means made operative consequent to the termination of the driving period of the selective switch for unbarring the said barred switches and for disabling the control of the control relay set from the selector last using it.
13. In a telephone system, calling lines, a plurality of selective switches having individual driving mechanisms, a control relay set common to said switches, selective means for associating the control relay set with any of said selective switches, means for linking a calling line to a said selective switch, means operative consequent to the said linking operation for barring other said selectors against seizure by way of linking a second calling line, means for causing the control relay set to be associated with the said selective switch resultant to it becoming linked, and means made operative consequent to the termination of the driving period of the selective switch for unbarring the said barred switches and for operatively disconnecting the control of the control relay set from the selector last using it, restoring the control relay set subject to the control of the first said selective switch to become linked to a selective switch thereafter, while retaining its inoperative connection with the last said switch operated.
14. In a telephone system, a plurality of line switches, a plurality of selective

- switches subject to being seized by the line switches, a control relay set, means for connecting the said set with any said switch seized to adapt the said seized switch to be 5 subject to directive control and to bar the other of the said switches against being seized, means for controlling the said seized switch whereby it will seize an accessible line, and means made operative consequent 10 upon the said switch seizing the said line whereby the said bar is removed from the said other switches and the said set is rendered subject to the control of the first of the said switches thereafter seized.
- 15 15. In a telephone system, a group of selective switches, a driving control relay set as a component element of the respective said switches common thereto, selective means responsive to seizure of any one of 20 said switches for selecting the seized switch and connecting the relay set thereto, and audible indicating means automatically operative consequent upon the driving control relay set becoming connected with the 25 seized switch.
16. In a telephone system, a group of selective switches, a driving control relay set as a component element of the respective said switches common thereto, selective 30 means responsive to seizure of any one of said switches for selecting the seized switch and connecting the relay set thereto, and a tone source and means for applying it to the talking circuits of the said switch upon 35 the relay set becoming connected to the said switch.
17. In a telephone system, a group of selective switches, a driving control relay set for said switches common thereto, a hunting 40 means made operative responsive to the seizure of a said switch for connecting the said relay set to the exclusive use of the said seized switch, and means automatically self initiated forthwith following the full 45 operation of the seized selective switch to disconnect the said driving control relay set from operative control thereof and to thereupon render the driving control relay set in control of any one of the switches of the 50 group irrespective of whether or not there is another call to the last said switches or whether the hunting means has reoperated.
18. In a telephone system, a group of selective switches, a driving control relay set for said switches common thereto, a hunting means made operative responsive to the seizure of a said switch for connecting the 55 said relay set to the exclusive use of the said seized switch, means automatically self initiated forthwith following the full operation of the seized selective switch to disconnect the said driving control relay set from operative control thereof and to thereupon render the driving control relay set in con- 60
- trol of any one of the switches of the group 65 irrespective of whether or not there is another call to the last said switches or whether the hunting means has reoperated, and means responsive to the seizure of another one of the selective switches of the 70 group while the first one is still busy to bar any idle selective switch of the group against seizure.
19. In a telephone system, a group of selective switches, a driving control relay set 75 for said switches common thereto, a hunting means made operative responsive to the seizure of a said switch for connecting the said relay set to the exclusive use of the said seized switch, means automatically self 80 initiated forthwith following the full operation of the seized selective switch to disconnect the said driving control relay set from operative control thereof and to thereupon render the driving control relay set in control of any one of the switches of the group 85 irrespective of whether or not there is another call to the last said switches or whether the hunting means has reoperated, and means responsive to the seizure of another one of the selective switches of the 90 group while the first one is still busy to bar any idle selective switch of the group against seizure, until the last seized selective switch has been fully operated. 95
20. In a telephone system, a plurality of groups of trunking switches, a plurality of groups of trunk lines each line leading to one of said trunking switches, a common control relay for each group of trunking switches 100 normally operatively related thereto, groups of calling lines leading to groups of corresponding selective switches, each of the latter said switches having access to a said group of trunking switches, the groups of trunking switches and the groups of selective 105 switches not corresponding, each of the said selective switches having access to only one trunking switch related to a common relay.
21. In a telephone system, a plurality of groups of trunking switches, a plurality of groups of trunk lines each line leading to one of said trunking switches, a common control relay for each group of trunking switches normally operatively related thereto, calling lines leading to selective switches, each of the latter said switches having access to a said group of trunking switches, each of the said selective switches having access to only one trunking switch related to 110 a common relay. 115
22. In a telephone system, a plurality of groups of trunking switches, a plurality of groups of trunk lines each line leading to one of said trunking switches, a common control relay for each group of trunking switches normally operatively related thereto, groups of calling lines leading to groups 120
- 125

of corresponding selective switches, each of the latter said switches having access to a said group of trunking switches, the groups of trunking switches and the groups of selective switches not corresponding, each of the said selective switches having access to only one trunking switch related to a common relay, and automatic means operative upon a trunking switch becoming seized to associate its said common relay into operative relation with it.

23. In a telephone system, a plurality of groups of trunking switches, a plurality of groups of trunk lines each line leading to one of said trunking switches, a common control relay for each group of trunking switches normally operatively related thereto, calling lines leading to selective switches, each of the latter said switches having access to a said group of trunking switches, each of the said selective switches having access to only one trunking switch related to a common relay, and automatic means operative upon a trunking switch becoming seized to associate its said common relay into operative relation with it.

24. In a telephone system, a plurality of groups of trunking switches, a plurality of groups of trunk lines each line leading to one of said trunking switches, a common control relay for each group of trunking switches normally operatively related thereto, groups of calling lines leading to groups of corresponding selective switches, each of the latter said switches having access to a said group of trunking switches, the groups of trunking switches and the groups of selective switches not corresponding, each of the said selective switches having access to only one trunking switch related to a common relay, automatic means operative upon a trunking switch becoming seized to associate its said common relay into operative relation with it, and means operative incidental to the seizure by a said trunking switch to disconnect its said relay from operative relation with it.

25. In an automatic telephone system, a group of selective switches, a driving control relay set for said switches common thereto, a fixed set of terminals for each switch cooperative for being swept with a set of movable terminals of the said relay set, a hunting means made operative responsive to the seizure of a said switch for connecting said relay set through a said fixed set of terminals and thereby setting the said movable set of terminals for the exclusive use of the said seized switch, an impulse relay of the said set for operative control of the selective switch with which the said relay set is set, and means for disabling the said impulse relay from affecting passed over terminals during the said hunting operation.

26. In an automatic telephone system, a

line switch, a first selective switch at normal, leading-in talking conductor terminals for said first selective switch, a busy conductor terminal for said first selective switch, a relay in the said first selective switch operative responsive to a circuit path closure including the busy terminal by the line switch, a second selective switch, means for setting the first selective switch into connective relation with the said second selective switch, means in the second selective switch for maintaining the said relay energized, and means controlled over the talking conductors for deenergizing the relay.

27. In a telephone system, a group of selective switches, a driving control relay set for said switches and component thereof, selective means responsive to the seizure of any one of said switches for selecting the seized switch and for connecting said relay set thereto, and means for retaining the selective means in its selected position until another one of said switches is seized.

28. In a telephone system, a group of selective switches, a driving control relay set for said switches and component thereof, selective means responsive to the seizure of any one of said switches for selecting the seized switch and for connecting said relay set thereto, means for retaining the selective means in its selected position until another one of said switches is seized, and means responsive to again seizing said seized switch in a new call for re-connecting the relay set thereto without re-operating said selective means.

29. In a telephone system, a group of selective switches, a driving control relay set for said switches common thereto, selective means responsive to seizure of any one of said switches for selecting the seized switch and connecting the relay set thereto, and means responsive to re-seizure of said seized switch in a new call for re-connecting the relay set thereto without re-operating said selective means.

30. In a telephone system, a group of selective switches, a driving control relay set for said switches common thereto, selective means responsive to the seizure of any one of said switches for selecting the seized switch and for connecting said relay set thereto, means for retaining the selective means in its selected position corresponding to the switch seized until another one of said switches is seized, and means thereupon operative to re-operate the selective means from its said position to select the said another switch seized and for connecting said relay set thereto.

31. In a telephone system, a group of selective switches, a plurality of driving control relay sets for said switches common thereto and component thereof, and selective

- means including a non-retracting wiper and responsive to the seizure of any one of said switches for selecting the seized switch and for connecting only one of said relay sets thereto.
32. In a telephone system, a group of selective switches, a plurality of driving control relay sets for said switches common thereto and component thereof, selective means including a non-retracting wiper and responsive to the seizure of any one of said switches for selecting the seized switch and for connecting only one of said relay sets thereto, and means for thereupon baring the remaining said driving control relay sets from connecting with the seized switch.
33. In a telephone system, a group of selective switches, a plurality of driving control relay sets for said switches common thereto and component thereof, selective means including a non-retracting wiper and responsive to the seizure of any one of said switches for selecting the seized switch and for connecting only one of said relay sets thereto, means for thereupon baring the remaining said driving control relay sets from connecting with the seized switch, and selective means operable responsive to another one of said selective switches being seized while first said connected relay is still connected to said first seized switch for selecting the last switch seized and for connecting another of said relay sets to last said switch seized.
34. In a telephone system, a group of selective switches, a plurality of driving control relay sets for said switches common thereto and component thereof, a selective means specific for each one of said sets, means responsive to the seizure of any one of said switches for causing each said selective means to operate to select the said seized switch, means whereby but one said selective means can connect its specific relay set to the selected switch, and means operated responsive to said connecting for disabling the other said selecting means.
35. In a telephone system, a group of selective switches, a plurality of driving control relay sets for said switches common thereto and component thereof, a selective means specific for each one of said sets, means responsive to the seizure of any one of said switches for causing each said selective means to operate to select the said seized switch, means whereby but one said selective means can connect its specific said relay set to the selected switch, means operated responsive to said connecting for disabling the other said selecting means, means operated responsive to another said switch being seized while the connected said relay set is maintained connected with the first said switch seized for causing the remaining said selective means to operate to select the last switch seized, and means whereby but one said remaining selective means can connect its specific said relay set to the last selected switch.
36. In a telephone system, a first selective switch, a second selective switch, a trunk line comprised of two talking conductors and a busy-test conductor, means for seizing said second switch over the said conductors by said first switch, and means exclusive of said talking conductors controlled over the busy-test conductor responsive to the seizure for maintaining the first switch in seized relation with the second switch.
37. In a telephone system, a first selective switch, a second selective switch, a trunk line comprised of two talking conductors and a busy-test conductor, means for seizing said second switch over the said conductors by said first switch, and a relay in the second switch actuated over the busy-test conductor and exclusive of said talking conductors for maintaining the seizure of the first switch with the second switch controlled over said busy-test conductor.
38. In a telephone system, a first selective switch, a second selective switch, a trunk line comprising a busy-test conductor, a relay of said second switch, means operative responsive to the first switch seizing the second switch for actuating the relay over said conductor, and means controlled solely by said relay for maintaining the seizure of the first switch with the second switch over said conductor.
39. In a telephone system, a first selective switch, a second selective switch, a trunk line comprised of two talking conductors and a busy test conductor, means for seizing said second switch over the said conductors by said first switch, and means exclusive of said talking conductors for establishing a locking circuit for preventing the restoration of the first selective switch.
40. In a telephone system, a first selective switch, a second selective switch, a trunk line comprised of two talking conductors and a busy-test conductor, means for seizing said second switch over the said conductors by said first switch, means exclusive of said talking conductors for establishing a locking circuit for preventing the restoration of the first selective switch, and means the operation of which is non-directively initiated for unlocking said locking circuit.
41. In a telephone system, a calling line, a first selective switch, a second selective switch, a trunk line comprised of two talking conductors and a busy-test conductor, means directly controlled over the calling line for seizing said second switch by the first switch, a relay of the second switch, and means operative solely over the busy-test conductor to operate the relay to close

a self-locking circuit for maintaining the first switch in seized relation with the second switch.

42. In a telephone system, a calling line, 5 a first selective switch, a second selective switch, a trunk line comprised of two talking conductors and a busy-test conductor, means directively controlled over the calling line for seizing said second switch by 10 the first switch, a relay of the second switch, means operative solely over the busy-test conductors to operate the relay to close a self-locking circuit for maintaining the first switch in seized relation with the second 15 switch, and means the operation of which is non-directively controlled for unlocking said locking circuit.

43. In a telephone system, a calling line, 20 a first selective switch, a second selective switch, a trunk line comprised of two talking conductors and a busy-test conductor, means directively controlled over the calling line for seizing said second switch by the first switch, a relay of the second switch, 25 means operative solely over the busy-test conductor to operate the relay to close a self-locking circuit for maintaining the first switch in seized relation with the second switch, and means the operation of which is 30 non-directively controlled for unlocking said locking circuit to thereby destroy said seizure.

44. In an automatic telephone system, a selective switch, a leading-in private conductor of the selective switch, an antecedent 35 switch for seizing the private conductor, means for maintaining the antecedent switch in seizure with the private conductor only by applying ground potential back from the selective switch over the private conductor 40 to the antecedent switch, and means for applying ground potential ahead from said antecedent switch over the seized private conductor to cause ground potential to be thereupon applied back over said private 45 conductor from the selective switch to the antecedent switch.

45. In a telephone system, a calling line, 50 a called line, a selective switch, means for automatically operating the switch from normal to form a link of a connection between the calling line and the called line, a release magnet of the switch operable for restoring the switch to normal from operated position, a contact closed only at off- 55 normal positions of the switch, a sole relay of the switch, and a circuit including a sole relay contact pair and on said relay for energizing the release magnet for operating it to effect the restoration of said switch. 60

In witness whereof, I hereunto subscribe my name this 1st day of March A. D., 1922.

HERBERT M. FRIENDLY.
